RADIO RECEIVING SYSTEM

Filed Dec. 22, 1920

Inventor:
John Mills.

by C. L. Sprague. Atty

UNITED STATES PATENT OFFICE.

JOHN MILLS, OF WYOMING, NEW JERSEY, ASSIGNOR TO WESTERN ELECTRIC COMPANY, INCORPORATED, OF NEW YORK, N. Y., A CORPORATION OF NEW YORK.

RADIO RECEIVING SYSTEM.

Application filed December 22, 1920. Serial No. 432,415.

To all whom it may concern:

Be it known that I, JOHN MILLS, a citizen of the United States, residing at Wyoming, in the county of Essex, State of New Jersey, have invented certain new and useful Improvements in Radio Receiving Systems, of which the following is a full, clear, concise, and exact description.

This invention relates to a radio receiving system and more particularly to a method of and means for protecting the receiving device of a radio system from interference due to static or natural atmospheric conditions.

15 The primary object of this invention is to eliminate interference due to that portion of the static which is received at long wave lengths and is essentially uniform in time and in intensity over a geographical area 20 of about the radius of one wave length, sometimes referred to as of the undirected or vertical type.

An additional object of the invention is the provision of a receiving system having 25 means for increasing the energy of the received signal waves without correspondingly increasing the energy of interfering waves such as static.

30 A further object consists in increasing the frequency of the received waves at a receiving station in order to enable greater discrimination against long interfering waves. In accordance with this invention, the incoming waves are received at two stations 35 so placed that signal waves incident upon their antennæ are 180° out of phase and are separately utilized to modulate waves of a much higher frequency than the received waves. The modulated waves are transmitted from two stations radiating a small amount of power to a local receiving station 40 symmetrically placed relatively to said two transmitting stations. Interfering waves of various kinds including static of the vertically directed type affect the two antennæ simultaneously, whereas the signal waves are 45 180° out of phase and hence the former are balanced in their effect upon the ultimate receiving antenna but the signal waves are additive. Since the distance over which 50 transmission takes place is relatively short, no particular difficulty will be experienced in making the ratio of signal to static current at the ultimate receiving station so

large that no loss of intelligibility occurs at 55 this station.

The single figure of the drawing illustrates a simple circuit arrangement embodying the invention.

Referring to this figure, A and B are two 60 receiving stations spaced apart a distance equal to one-half the wave length of the signal wave to be received, each provided with an antenna 1 which may or may not be resonant to the frequency of the incoming sig- 65 nal waves.

Each antenna is coupled by the transformer 3 to a resonant circuit 4 tuned to the frequency of the incoming signal waves. These tuned circuits are connected across the 70 input circuits of amplifiers 5 of any well-known construction but which may be of the vacuum tube type, the output circuits of which are coupled by transformers 6 to the input circuits of modulators 7. Carrier 75 sources 8, adapted to supply current of the same but a very much higher frequency than that employed for signaling purposes, are connected in the input circuits of the modulators 7. The output circuits of the modulators are each coupled by a transformer 9 to a transmitting antenna 10.

As thus far described, the operation of this system is as follows: An incoming mixture of static and signal currents absorbed 85 by the receiving antennæ is amplified in the main receiving stations and applied by the transformers 6 to modulate the high frequency current supplied by the sources 8, the modulated carrier waves being radiated 90 by the antennæ 10.

The currents supplied by the sources 8 to the modulators 7 should be of the same frequency, which may be, a higher harmonic of the incoming signal waves, though this 95 relation is not essential, and can be derived from a single source, as for example, from the incoming signal itself by means of a harmonic generator located at each of the stations A and B.

100 The transmitted waves from these two stations are received at a common receiving station C which is provided with an antenna 12, coupled by a transformer 13 to a circuit, which is selective of the frequency of the 105 radiated waves from the antennæ 10. These waves are detected by the device 15, herein shown by way of example as of the audion

type, and impressed upon the signal receiver 17 by the transformer 16. The antenna 12 should preferably be of the loop type, which, owing to its well known directional characteristic may be oriented, as to the received signals from stations A and B, in the proper relationship for the complete neutralization of the interfering energy which is transmitted from these stations.

10 Should it be found desirable, the high frequency current radiated from the local transmitting stations and received at the common receiving station, as well as the low frequency current supplied to the receiver, may be amplified.

Since the connection and operation of amplifiers are now well-known, it is believed that a detailed description of their circuits and operation is unnecessary.

20 The type of interfering waves assumed including static will produce only a feeble effect in the local receiving circuit, since these are of relatively low frequency compared with the natural period of the circuit 14,

25 while the locally radiated waves, of the frequency to which this circuit 14 is tuned, transmitted over a relatively short distance, will produce a strong effect. Thus, with a local station of small power, the ratio of 30 the signal to static current at the common receiving station may be made so great, or, in other words, the last-mentioned station may be made to discriminate so sharply between these two currents, that interference 35 will be substantially eliminated.

While certain circuits and specific details have been herein shown and described with the object of clearly and completely disclosing the invention which is primarily designed to suppress interference due to varying static conditions by an arrangement which does not require adjustment, it is to be understood that they are not essential elements of a system for the purpose disclosed.

45 Thus, any type of amplifier system, detector, modulator and modulating circuit may be used and the common receiving station may 50 occupy a non-symmetrical position relative to the two transmitting stations, the amount 55 of energy transmitted from the latter being regulated so as to produce the same effect at the former; though a symmetrical position is preferable.

Moreover, while this disclosure is limited to a radio receiving system, it is apparent that the principles of this invention are applicable to any radiant energy receiving system.

60 It is therefore obvious and it is to be understood that this invention is not limited to the arrangement herein set forth but only by the scope of the attached claims.

What is claimed is:

1. A method of receiving signal waves which comprises separately receiving a

plurality of sets of incoming waves, giving the received waves a definite phase relation, separately modulating a plurality of carrier waves by said received waves, transmitting said modulated waves over two radiant 70 energy paths, and receiving and combining the modulated waves, thereby suppressing interfering waves.

2. A method of receiving signal waves which comprises separately receiving two 75 sets of incoming waves, giving the received waves a definite phase relation and separately modulating two carrier waves by said waves, transmitting said modulated waves over two radio paths and receiving and combining the modulated waves.

3. The method of receiving radio signals of given wave length at points separated by a half wave length, modulating relatively high frequency carrier waves by the waves 85 respectively received thereat, transmitting the modulated waves over two radio paths and receiving and combining the modulated waves.

4. A radio receiving system comprising a 90 plurality of receiving stations spaced apart, means at each station for receiving incoming waves, means at each station for modulating a carrier wave by the received waves, means for transmitting the modulated waves from 95 a pair of antennæ and means for receiving the two sets of modulated waves at a single station.

5. A radio receiving system comprising a pair of receiving stations, means at each station for receiving incoming waves, means for modulating carrier waves by the separately received waves, means to determine a definite phase relation between the modulating waves, means for transmitting the 105 modulated waves from a pair of antennæ, a single antenna for receiving the two sets of modulated waves and a receiving circuit associated with the single antenna.

6. A radio receiving system comprising a 110 pair of receiving stations spaced a half wave length apart, means for receiving incoming waves thereat, means at each receiving station for modulating a carrier wave by the incoming waves, an antenna at each station 115 for transmitting the modulated waves and means for receiving and combining the two modulated waves at a single station.

7. A radio receiving system comprising a pair of receiving stations, means at each station for receiving incoming waves, means for modulating carrier waves of one frequency by the separately received waves, means to determine a definite phase relation between the modulating waves, means for transmitting the modulated waves from a pair of antennæ, a single antenna for receiving the two sets of modulated waves and a receiving circuit associated with the single antenna.

8. A radio receiving system comprising a pair of receiving stations spaced a half wave length apart, means thereat for receiving incoming waves, means at each station for modulating a carrier wave by the incoming mixture of static and signal waves, an antenna at each station for transmitting the modulated waves and a common receiving station for said modulated waves.
- 10 9. A radio receiving system comprising a pair of receiving stations spaced apart, means at each station for receiving incoming waves, means at each station for modulating a carrier wave by the received waves,
- 15 an antenna at each station for transmitting the modulated waves and a common receiving station for said modulated waves symmetrically placed with reference to said transmitting antennæ.
- 20 10. A radio receiving system comprising two receiving stations having means to determine a definite phase angle between two sets of waves received thereby, means to modulate two carrier waves by the received waves, means to transmit the two carrier waves from said stations and an ultimate receiving station having means to combine said two modulated waves.
- 25 11. A receiving system for signal waves adapted to suppress interfering waves comprising a plurality of stations spaced apart, each including wave receiving and transmitting apparatus, said transmitting apparatuses having means to increase the frequency of the received waves and a common receiving station for the waves of increased frequency.
- 30 12. A receiving system for signal waves adapted to suppress interfering waves comprising a plurality of signal stations spaced apart, each including wave receiving and transmitting apparatus, said transmitting apparatuses having means to increase the energy of the received waves and a common receiving station for the waves of increased energy.
- 35 13. A receiving system for signal waves adapted to suppress interfering waves comprising a plurality of signal stations each having wave receiving apparatus, means to increase the energy of the received waves and means to transmit waves of increased energy, and a common receiving station for the waves of increased energy cooperating with the transmitting means to discriminate in favor of the desired signal wave.
- 40 In witness whereof, I hereunto subscribe my name this 17th day of December A. D. 1920.
- 45
- 30 11. A receiving system for signal waves adapted to suppress interfering waves comprising a plurality of stations spaced apart, each including wave receiving and transmitting apparatus, said transmitting apparatuses having means to increase the frequency of the received waves and a common receiving station for the waves of increased frequency.
- 35 12. A receiving system for signal waves adapted to suppress interfering waves comprising a plurality of signal stations spaced apart, each including wave receiving and transmitting apparatus, said transmitting apparatuses having means to increase the energy of the received waves and a common receiving station for the waves of increased energy.
- 40 13. A receiving system for signal waves adapted to suppress interfering waves comprising a plurality of signal stations each having wave receiving apparatus, means to increase the energy of the received waves and means to transmit waves of increased energy, and a common receiving station for the waves of increased energy cooperating with the transmitting means to discriminate in favor of the desired signal wave.
